WASHING MACHINE

Thore Martin Elfving, Stockholm, Sweden

Application September 22, 1931, Serial No. 564,330, and in Sweden June 10, 1931

12 Claims. (Cl. 68—37)

The present invention relates to washing machines exclusively operated by heat. More particularly it relates to such washing machines in which the mechanical washing power is derived from intermittent pressure variations caused by intermittently cooled condensers disposed in the vapor space of a boiler. Such pressure variations will in turn compel the washing liquid to perform a reciprocating flow through or past the articles to be cleaned. In such machines it is a known measure to use the washing liquid proper as a medium for vapor development and to store the vapor formed in closed chambers disposed above the washing liquid level and provided with condensers. Such machines are described in the U. S. application No. 523,143. This known arrangement has, however, the inconvenience that if the washing liquid communicates directly with the atmosphere it will require a temperature of about one hundred degrees centigrade to start boiling. This temperature is often most unsuitable, particularly in case silk or woolen clothes have to be washed which require a considerably lower washing temperature.

The present invention has for its object to bring about the desired pressure changes in the apparatus without the necessity of heating the washing liquid proper to the boiling point. This is brought about by separating the vapor generator or boiler proper from the liquid in the washing chamber by means of a movable, yielding heat insulating partition whereby the vapor developed never will contact with the washing liquid or the washing chamber walls. The yielding partition may have various forms, it might, by way of example, consist of a diaphragm of rubber or any other suitable flexible material. In any case, this partition will serve the same purpose as a piston in a steam engine, on the one side of which an excess of pressure or a vacuum is exerted by the vapor generated in the boiler. The load on this "piston" is then constituted by the washing liquid and the articles disposed therein on the opposite side of the partition.

In washing apparatus operated by a periodical development and condensing of vapor it is very impractical to supply heat continuously during the condensing period as the steam developed during this period is not only a waste of energy but detrimental to the operation for the reason that the condensing is delayed and large cooling water quantities consumed. The invention, therefore, has also for its object to regulate the amount of heat supplied from the boiler heating

means, such as a gas burner, so that the heating power during the condensing period is reduced to a minimum and at the end of this period again restored to its normal value. This can be brought about by letting the gas supply be controlled by the motions of the movable diaphragm in shifting between the positions taken up during the pressure and condensing periods respectively, or by the provision of means for controlling the gas supply in dependency of the periodical water supply to the condenser. Both embodiments will be more closely described in the following.

It is of importance to provide a reliable device for the periodical supply of cooling water to the condenser and such a device is therefore also within the scope of this invention. According to the invention a siphon is adapted to draw cooling liquid from a liquid container to the condenser. Said container is provided with inlet means for the continuous supply of liquid, the input capacity of the inlet means being, however, considerably less than the output capacity of the siphon, whereby the container will be periodically emptied through the siphon whereby the condenser in the boiler is cooled intermittently.

In case the yielding partition between the washing chamber and the boiler is constituted by a diaphragm it is of great importance to avoid the occurrence of excessive pressures endangering the strength of the diaphragm. Therefore the invention provides for a safety device adapted to shut off the supply of gas to the burner in case the cooling water becomes scarce so that dangerous pressures in the boiler are avoided. There are also provided automatic shutting off means controlled by the pressure in the boiler so as to operate upon the pressure exceeding a predetermined value. By these means the gas is automatically restricted both in case the intervals of time between the cooling periods be too great or in case the cooling water supply should fail.

The invention will be more closely described with reference to the accompanying drawing showing an embodiment of the invention.

The machine comprises a washing chamber 1 having a bottom 2 preferably convex on its outside, from which the washing chamber communicates with the boiler or steam generator 3. The boiler is provided with a heating surface 4 enlarged by corrugation or in other suitable manner. The boiler is provided with a valve 5 disposed somewhat above the bottom of the boiler so that upon opening said valve a certain quan-

5 tity of liquid is retained in the boiler. The boiler is heated by a gas burner 6 or any other suitable heating means. Above the bottom of the wash-
 10 ing chamber 1 there is disposed a tightly sealing 6 yielding diaphragm 7 of rubber or the like which in its normal position conforms with the con-
 15 vexit of the washing chamber bottom. Above the yielding diaphragm separating the bottom 2 from the washing chamber proper there is dis-
 20 posed a detachable lid 8 having an opposite con-
 25 vexit to that of the washing chamber bottom 2. This lid 8 is provided with passages or apertures for the washing liquid so that said liquid may per-
 30 form a reciprocating flowing through the lid with-
 35 out displacing the washing articles 35. The lid 8 is detachably mounted by means of known fix-
 40 tures 9, such as bayonet clutches or the like, so that the lid upon being turned a fourth of a revolution may be detached from the washing
 45 chamber. The washing chamber is in open com-
 50 munication with the external air or atmosphere and is provided with a draw off valve 10. Wash-
 55 ing liquid and the articles to be washed 35 are put into the washing chamber 1 the articles or
 60 washing clothes being then carried by the lid 8 and preferably held in position by means of a
 65 perforated lid 11 disposed above and resting upon the articles during the washing. The boiler is
 70 filled with a small quantity of liquid which must
 75 not necessarily consist of water but may be any
 80 suitable evaporable liquid.

It has to be particularly noted that steam de-
 85 velopment and condensing in the boiler for gener-
 90 ating mechanical washing power accordingly
 95 takes place quite independently of the tempera-
 100 ture of the washing liquid. The boiler can thus
 105 be considered as a system entirely separated from
 110 the washing chamber proper which system trans-
 115 fers mechanical motion to the washing chamber
 120 through the intermedium of a yielding dia-
 125 phragm. Above the liquid level the boiler is pro-
 130 vided with a condenser coil 12 which through a
 135 funnel 13 is periodically supplied with cooling
 140 water from a siphon device 14 known per se which
 145 periodically draws water from the container 15.
 The container 15 is provided with an inlet pipe
 150 16 communicating with the water main and sup-
 155 plying a continuous inflow of water into the con-
 160 tainer the quantity of which is preferably restrict-
 165 ed by means of the choke cartridge 17. The con-
 170 denser coil has an outlet 18 for the waste water.
 The washing chamber proper may be provided
 175 with a surrounding covering 19 for conducting the
 180 combustion gases from the gas burner around
 185 the washing chamber thereby preventing the cool-
 190 ing of the washing liquid during the washing
 195 procedure. The machine is supported on a base
 200 33.

205 The gas burner 6 is supplied with gas through
 210 the gas pipe 20 having a number of regulating
 215 valve devices for controlling the gas supply so as
 220 to prevent the occurrence of excessive pressures
 225 in the boiler and to bring about an economical
 230 operation.

235 There is thus disposed a receptacle 21 communi-
 240 cating, on the one side, with the two ends 36, 37
 245 of the gas pipe and, on the other, with a pipe 24
 250 connecting the receptacle with the interior of the
 255 boiler 3. Fixed to the walls of the receptacle
 260 there is disposed a diaphragm 22 preferably of
 265 rubber which normally takes up the position
 270 shown on the drawing. Upon an increase in the
 275 boiler pressure, however, the diaphragm 22 will
 280 expand to the left on the drawing while restrict-
 285 ing the pipe opening 36. An excessive boiler
 290

295 pressure will thus reduce the fuel supply to the
 300 burner 6. There is also provided a narrow by-
 305 pass 38 to keep the gas flame alive always.

310 Through the float device 25 disposed in the
 315 water storing container 15 a gas valve 27 is oper-
 320 ated by the arm 26 in such a manner that the
 325 full gas current is let through during the move-
 330 ment of the float from its lowermost to its upper-
 335 most position. When the liquid in the container
 340 15 has risen to a certain level as indicated in full
 345 lines the valve 27 is shut and opened again when
 350 the float 25 during the discharge through the
 355 siphon 14 has sunk to a certain low level as indi-
 360 cated in dash and dot lines. During this period
 365 of restriction a certain small gas quantity will
 370 however, pass through a by-pass 28 of sufficient
 375 section to maintain the gas burner burning all the
 380 time.

385 A similar type of regulating device cooperates
 390 with the gas valve 29 included in the same gas
 395 pipe 20. The valve 29 is, however, here operated
 400 by the arcuate rod 31 cooperating with the arm
 405 30. The rod 31 is secured to the yielding dia-
 410 phragm and participates therefore in its move-
 415 ments. The connection is here adjusted in such
 420 a manner that the gas supply is shut off in the
 425 upper position of the diaphragm but again opened
 430 as soon as the diaphragm has reached its lower
 435 position. Also in this case the gas valve 29
 440 is provided with a by-pass 32 through which a
 445 sufficient gas quantity may pass also during the
 450 restricted period to hold the gas burner lit.

455 Attention is particularly called to the fact
 460 that arms 26 and 30 preferably are provided with
 465 lost motion devices 39 and 40 respectively to
 470 render possible the operation above described.

475 The washing machine operates in the follow-
 480 ing manner. The steam generator or boiler 3 is
 485 from the beginning filled with a small quantity
 490 of evaporable liquid, such as water, and also
 495 preferably evacuated so that the greater portion
 500 of the enclosed air is removed. The quantity of
 505 liquid in the boiler is preferably so small as pos-
 510 sible to obtain the shortest possible heating pe-
 515 riod and to reduce as much as possible the heat
 520 losses during the alternate periods of steam de-
 525 velopment and steam condensing. The wash-
 530 ing articles and the washing liquid having a
 535 temperature to suit the articles are inserted into
 540 the washing chamber above the lid 8 whereupon
 545 also the lid 11 is put in place. The gas burner
 550 6 is lit and at the same time the cooling water
 555 pipe is opened. After the gas burner has been
 560 lit the small water quantity in the boiler is rapid-
 565 ly heated to the boiling point whereupon the
 570 steam development starts. In the same measure
 575 as the pressure increases in the boiler the yield-
 580 ing diaphragm 7 is forced from its lower pos-
 585 ition 7 to its uppermost position 34 indicated in
 590 dash and dot lines. The diaphragm 7 then pushes
 595 the portion of the washing liquid confined be-
 600 tween the positions 7 and 34 upwards and forces
 605 it to pass the articles or otherwise bring about
 610 powerful currents in the washing chamber
 615 whereby a mechanical cleaning effect is obtained.
 620 As soon as the container 15 is filled with cooling
 625 water the siphon 14 starts operation and draws
 630 cooling water to the cooling coil 12 whereby con-
 635 densing of the steam takes place in the boiler 3.
 640 On account of the rapid reduction in pressure
 645 in the boiler caused thereby the rubber dia-
 650 phragm 7 is retracted to its position 7 which re-
 655 sults in a violent liquid current in the washing
 660 chamber in opposite direction. As soon as the
 665 cooling water supply has ceased on account of
 670

675

the siphon 14 having emptied the container 15 a steam development period starts again and so on. The immediate output capacity of the siphon is essentially greater than the input capacity of the described inlet valve. This condition is quite positive as otherwise a periodical emptying action of the siphon would be impossible. If for example the output capacity of the siphon were equal or smaller than the input capacity of the inlet valve, the water level in the vessel 15 would remain stationary or rise respectively in proportion to the difference between input and output. The flow through the siphon would then never cease. If now the inlet valve is restricted to just such an extent that the input through the valve falls slightly below the output through the siphon, the water level will fall in proportion to the difference between the output and the input until the mouth of the siphon 14 in the vessel 15 is reached or passed, when the flow through the siphon will at once cease. As there is no output, the inlet valve will now prevail and fill the vessel to the higher level indicated on the drawing, whereupon the emptying operation of the siphon again starts automatically, and so on.

In the manner described above, a powerful reciprocating flow of washing liquid is obtained in the washing chamber. This reciprocating pumping of liquid is caused by the alternate excess of pressure and vacuum respectively in the boiler whereby it is rendered possible to produce very great forces and a very strong mechanical washing action. On account of the heat insulating properties of the diaphragm the washing liquid in the washing chamber must not necessarily have the same temperature as the boiling temperature of the liquid in the boiler. If water is used both as washing liquid and as evaporable medium in the boiler it has been found that the temperature of the washing liquid may be down to thirty or forty degrees centigrade without obstructing the steam development in the boiler normally taking place at a temperature of one hundred degrees centigrade. The machine is therefore particularly suitable for washing silk and woolen articles. The advantages are also enhanced by the fact that the washing method is very harmless for more delicate articles as no hard mechanical parts work thereon. The power developed by the boiler in the reciprocating movement of the rubber diaphragm may be utilized in various manners in the washing liquid. The lid 8 may thus, by way of example, be provided with nozzles through which the water is pressed in powerful jets in which case the kinetic energy developed may be used for washing purposes.

During the condensing period the gas burner should, of course, not operate with a full gas current as the heat then supplied only obstructs the condensing desired. The gas quantity supplied to the burner should therefore be regulated in time with the intermittent cooling so that the gas current during the flow of water through the condenser coil is restricted to a minimum amount and increased as much as possible during the period of steam development during which period the cooling coil is empty. This may take place by means of the regulating device above described in which the float 25 in the water container 15 regulates the gas quantity in time with the cooling water supply whereas another device by means of a gearing 30, 31 transfers motion from the yielding dia-

phragm 7 to a valve 29 to regulate the gas quantity in correspondence to the diaphragm position. The latter device is very important as at the same time security against overheating is obtained in case the cooling water supply for any reason should fail. If the cooling water supply is shut off the gas development will take place until the diaphragm 7 is forced up to its upper position 34 in which, however, the gas supply is choked by means of the valve 29 so that the steam development stops. There is also another safety device which starts operation upon the failure of cooling water, i. e. the device 21 shutting off the gas supply upon the pressure in the boiler 3 reaching a certain predetermined value which depends upon the dimensioning of the diaphragm 22 and should be selected higher than the pressure required for developing normal washing effect.

In a washing apparatus of the kind above described a very powerful reciprocating motion of washing liquid is obtainable whereby an efficient mechanical washing action is obtained without using any movable parts which may wear or destroy the clothes. It is possible to let the boiler operate as a steam engine with a high efficiency at about atmospheric pressure and at a temperature corresponding to that of the boiling liquid, while at the same time a lower or higher temperature of the washing liquid is maintained, without disturbing the boiler operation or the movements of the rubber diaphragm. The boiler proper should preferably be insulated to obtain the best possible economy with the heat supplied. Further the condenser surface should have a certain relation to the steam quantity developed so that an efficient condensing takes place with the least possible water quantity. The condenser should therefore have the greatest possible surface for bringing about the strongest possible pressure variation. The bottom of the washing chamber constituting at the same time a wall of the boiler must be insulated from the other parts of the washing chamber which preferably may be done by clamping the edges of the rubber diaphragm between the chamber wall and the bottom as may be seen from the drawing.

By a boiler entirely separated from the washing chamber and operating with a very small liquid quantity a very short starting time and very small operating losses are obtained. On account of the pressure variations in the boiler the boiler liquid will, of course, change its boiling point which results in a loss of liquid heat for each stroke being equal to the liquid quantity multiplied by the variation in boiling temperature in degrees centigrade. If the liquid quantity in the boiler is maintained very small this loss may therefore be reduced to a negligible quantity in comparison with radiation losses etc.

By the present invention a very satisfactory gas operated washing machine is brought about which is suitable for all kinds of washing articles and which possesses a very high efficiency referred to the heat supply. By the above described safety devices a complete security is obtained that no mistakes in manipulating the machine or any failure in the water supply may cause any accidents in operation.

I claim:-

1. A washing machine having a washing chamber adapted to contain a washing fluid, a boiler disposed below said chamber, a liquid tight yielding partition separating said washing cham-

- ber from said boiler and forming the bottom of the former, means for heating said boiler to form vapor therein to cause the partition to move, and means for intermittently condensing the vapor formed. 80
2. A washing machine having a washing chamber adapted to contain a washing fluid, a boiler closed to the atmosphere, by a liquid tight yielding partition separating said washing chamber from said boiler, means for heating said boiler to form vapor therein in order to cause the partition to move and means for intermittently condensing the vapor formed. 85
3. A washing machine having a washing chamber adapted to contain a washing fluid, a boiler closed to the atmosphere, by a liquid tight yielding partition separating said washing chamber from said boiler, means for heating said boiler to form vapor therein in order to cause the partition to move, means for intermittently condensing the vapor formed, and means for holding the articles to be washed in definite positions in the washing chamber. 90
4. A washing machine having a washing chamber adapted to contain a washing fluid, a boiler in said machine which is closed to the atmosphere, by a liquid tight yielding partition separating said washing chamber from said boiler, means for heating said boiler to form vapor therein in order to cause the partition to move, means for intermittently condensing the vapor formed, a cooling liquid container having inlet means for providing a continuous supply of liquid, and a siphon adapted to draw cooling liquid intermittently from said container to the condensing means, the immediate output capacity of the siphon being essentially greater than the input capacity of the inlet means in order to ensure a periodical emptying action of said siphon. 95
5. A washing machine having a washing chamber adapted to contain a washing fluid, a boiler in said machine closed to the atmosphere, by a liquid tight yielding partition separating said washing chamber from said boiler, heating means for heating the boiler to form vapor therein in order to cause the partition to move, means for condensing the vapor formed, means for intermittently passing cooling liquid through said condensing means, a heating energy supply valve for controlling the amount of heat developed by said heating means, and operable means controlled by the cooling liquid for intermittently shifting said valve according to the cooling liquid flow. 105
6. A washing machine having a washing chamber adapted to contain a washing fluid, a boiler closed to the atmosphere, by a liquid tight yielding partition separating said washing chamber from said boiler, heating means for heating the boiler to form vapor therein in order to cause the partition to move, means for condensing the vapor formed, means for intermittently passing cooling liquid through said condensing means, a heating energy supply valve for said heating means, and operable means controlled by the cooling liquid adapted to hold said valve in a restricted position during the condensing period while cooling liquid is passed through the condensing means, and also to hold the valve device in open position during the non-condensing period. 110
7. A washing machine having a washing chamber adapted to contain liquid, a boiler closed to the atmosphere, by a liquid tight yielding parti-
- tion separating said washing chamber from said boiler, heating means for heating the boiler to form vapor therein in order to cause said partition to move, means for intermittently condensing the vapor formed, a heating energy supply valve for controlling the amount of heat developed by said heating means, and means connected with the yielding partition for shifting said valve intermittently according to the partition movements. 115
8. A washing machine having a washing chamber adapted to contain washing liquid, a boiler closed to the atmosphere, by a liquid tight yielding partition separating said washing chamber from said boiler, which is yieldable between expanded and retracted positions, heating means for heating the boiler to form vapor therein in order to cause the partition to move, means for intermittently condensing the vapor formed, a heating energy supply valve shiftable into restricted and open positions for controlling the amount of heat developed by said heating means, and means connected with said yieldable partition for holding the valve in a restricted position in the expanded position of the partition and in open position in the retracted position of the partition. 120
9. A washing machine having a washing chamber adapted to contain washing liquid, a boiler closed to the atmosphere, by a liquid tight yielding partition separating said washing chamber from said boiler and yieldable between expanded and retracted positions, heating means for heating the boiler to form vapor therein to cause the partition to move, means for intermittently condensing the vapor formed, a heating energy supply valve shiftable into restricted and open positions for controlling the amount of heat developed by said heating means, and operable means connected with the partition to shift the valve device into restricted position during and before the end of the expansion movement of the partition and into open position during and before the end of the retraction movement of the partition. 125
10. A washing machine having a washing chamber adapted to contain washing liquid, a boiler closed to the atmosphere, by a liquid tight yielding partition separating said washing chamber from said boiler, heating means for heating the boiler to form vapor therein in order to cause the partition to move, means for intermittently condensing the vapor formed, a heating energy supply valve for controlling the amount of heat delivered to the boiler by said heating means, and valve operating means communicating with the boiler for restricting the opening of the valve at excess pressures in said boiler. 130
11. A machine having a chamber adapted to contain a fluid, a boiler closed to the atmosphere, by a liquid tight yielding partition separating the interior of said chamber from said boiler, means for heating said boiler to form vapor therein in order to cause the partition to move, means for intermittently condensing the vapor formed. 135
12. A machine having a chamber adapted to contain a fluid, a boiler closed to the atmosphere, by a liquid tight yielding partition separating the interior of said chamber from said boiler, means for heating said boiler to form vapor therein in order to cause the partition to move, means for intermittently condensing the vapor formed, and means for holding articles to be treated in definite positions within the chamber. 140

THORE MARTIN ELFVING.
